UNITED STATES PATENT OFFICE.

WILLIAM E. SWINDELL, OF EAST ORANGE, NEW JERSEY.

DESIGN FOR A BOTTLE OR SIMILAR CONTAINER.

Application filed September 3, 1927. Serial No. 23,284. Term of patent 3½ years.

To all whom it may concern:

Be it known that I, WILLIAM E. SWINDELL, a citizen of the United States, residing at East Orange, county of Essex, and State of New Jersey, have invented a new, original, and ornamental Design for Bottles or Similar Containers, of which the following is a specification, reference being had to the accompanying drawing, forming a part thereof.

I claim:

The ornamental design for a bottle or similar container, as shown.

WILLIAM E. SWINDELL.
